CIRCUIT BREAKER

Winthrop M. Leeds, Wilkinsburg, Pa., assignor
to Westinghouse Electric & Manufacturing
Company, a corporation of Pennsylvania

Original application May 20, 1930, Serial No.
453,909. Divided and this application November
11, 1933, Serial No. 697,647

44 Claims. (Cl. 200—150)

My invention relates to circuit-interrupters and particularly to arc-extinguishing devices therefor. This application is a division of my copending application Serial No. 453,909 filed May 5 20, 1930.

In Patent No. 1,899,605 of B. P. Baker, et al., issued February 28, 1933 and assigned to the assignee of this application, an arc-extinguishing device is disclosed comprising a plurality of 10 insulating and magnetic plates arranged in stacks to constitute arc-extinguishing structures and containing aligned slots adjacent to an arc path that is established between separated contact members. The arc, so established, is moved into 15 the slots where it is deionized and extinguished because of the distortion of the surrounding field in the presence of magnetic plates.

Supplementing this structure, the present application has for its object a more effective arrangement and location of the slots in the plates to provide deeper slots and a greater distance over which the arc may travel in order that the speed of arc movement may be increased.

A further object of my invention is to provide 25 a radial magnetic field associated with the lower part of an arc-extinguishing device of the above described type that shall produce an increased magnetomotive force for moving the arc when the current thereof is below a predetermined 30 value.

For a more complete understanding of the nature and objects of my invention, reference may be had to the following description, taken 35 in conjunction with the accompanying drawing wherein:

Figure 1 is a sectional view, in elevation, of a circuit interrupter embodying my invention.

Fig. 2 is a plan view on an enlarged scale of 40 a modified arc-extinguishing device embodying my invention, having a conducting plate provided on the top thereof upon which the arc terminal may be moved and having pockets for retaining oil.

Fig. 3 is a sectional plan view of an arc-extinguishing device embodying my invention, taken on the line III—III of Fig. 4, and

Fig. 4 is a vertical sectional view of the device shown in Fig. 3, taken along the line IV—IV thereof.

My invention comprises, in general, a casing 1 having a cover 2 thereon that supports conductor bushings 3 and 4 in a manner that is well known in the art. The bushings 3 and 4 support the terminal members 5 and 6, respec-

tively, which are conductively joined by a movable bridging member 7.

A lift rod 8 supports the bridging member 7 and extends through the cover 2 where it is actuated by a mechanism (not shown) to operate the bridging member to open and to closed position. Arc-extinguishing structures 9 are supported on the terminal members 5 and 6, respectively and are immersed in a quenching liquid 11 contained within the casing 1.

The arc-extinguishing device 9 comprises a plurality of insulating plates 16 having curved slots 15 and built up into a stack having a plurality of magnetic plates 17 distributed throughout its length and insulated by insulating liners 18. A vent 13 is provided from the slot 15.

When the arc is drawn, by movement of the bridging member 7, away from the terminals 5 and 6, the magnetomotive force set up in the magnetic plates 17 so distorts the magnetic field 20 about the arc that the arc is normally moved toward the closed end of the slot 15. The gases generated by the decomposition of the quenching fluid 11 in the slot 15, as a result of the intense heat of the arc, are disposed within the slot 25 between the arc and the inner end thereof and are forced through the arc as it is moved toward the rear of the slot to deionize it, the gases then escaping through the vent 13.

The curved path of the slots 15 provides an 30 increased slot depth without increasing the outside dimensions of the arc-extinguishing device, in order to make possible the movement of the arc by magnetic means at higher velocities. In the modification shown in Fig. 2, pockets 19 in alternate plates 16 are formed by providing narrowed portions along the periphery of the curve 15 so that the fluid is trapped and retained so as to be available for feeding into the arc as 40 the arc is moved through the slot. Other plates 16 are formed with a narrow curved slot 15 which converges in width in the direction of arc movement. These plates provide inwardly projecting longitudinally spaced ribs along the 45 arc passage which serve to restrict the arc in sections as it is moved along the passage.

A metal plate 20 is provided on the top of the arc-extinguishing device 9, as shown in Figs. 1 and 2. The stationary terminal members 5 and 6 are directly adjacent and electrically connected to the plates 20 upon which the arc terminals are transferred and moved during the downward movement of the bridging member 7. By moving the arc terminal across the plate, the upper plates 55

of the stack are utilized more efficiently, the arc is lengthened in the general shape of a helix, the upper contact has a longer life, since the burning is distributed over a greater area, and re-striking of the arc is more difficult, since the upper hot arc terminal is moved away from the position directly above the lower arc terminal on the bridging member.

The arc is moved into the slot 15 under the action of the magnetic field due to the arc current. This field around the arc stream is distorted due to the open-ended slot in the iron plates 17 and thus exerts a force on the arc to move it into the slot. The strength of the magnetic field which moves the arc into the slot therefore depends on the magnitude of the arc current, and when small currents are interrupted, there will be a relatively small force to move the arc into the slot. This motion of the arc is opposed by the outward flow of the gas formed by the decomposition of the arc extinguishing fluid trapped in the slot. In some cases with small currents the magnetic field set up by the single turn formed by the arc may not be sufficient to overcome the force exerted by the gas so that the arc is not moved into the slot.

Where the current to be interrupted is large, there is a strong magnetic field to rapidly move the arc into the slot. This causes the generation of a large amount of deionizing gas which is moved through the arc, resulting in its extinction before the moving contact has moved the whole length of the stack of plates. To interrupt smaller currents it may be necessary to draw the arc the whole length of the stack before it is extinguished.

As pointed out above, when the current is less than a predetermined amount, the gas pressure, built up ahead of the arc, may overcome the magnetic driving force produced by the presence of the iron plates 17 and tend to force the arc back out of the slot 15.

To prevent such movement, I provide a plurality of pairs of windings 21 and 22 that are adapted to be connected in series with the arc, if it becomes a predetermined length, as shown in Figs. 3 and 4. When the arc current is above the predetermined value, the arc will be extinguished before it becomes elongated sufficiently to insert the windings 21 and 22 in circuit therewith. When, however, the arc current is below this value, the arc will be drawn the full length of the slot before it is extinguished and will be broken up into a plurality of sections by conducting plates 23 having the windings 21 and 22 inserted in series therewith.

The windings 21 and 22 are differentially associated with each other to produce magnetic fields in the same direction across the upper and lower air gaps 24 of the iron circuit 25 of each section as indicated by arrows 31 and 32. The iron path 25 is provided as a common return for the flux from both air gaps. Conducting plates 23 are connected to each of the windings 21 and 22 and are so placed that the terminals of the sectionalized arc are moved thereon. Insulation 26 is provided between the windings 21 and 22 and the iron circuit 25 and also between adjacent sets of windings of the structure. The slotted section and the insulating plates are held together to form a unit structure by a through bolt 27.

In this construction, when an arc is established by the bridging member 7, the plates 17 so distort the magnetic field about the arc that

the arc is moved along in the slot 15 where, if the arc current is sufficiently large, the arc will be extinguished before it is drawn the full length of the slot.

On the other hand, if the arc current is insufficient, in the presence of the plates 17, to produce this movement, the arc extinction will be delayed and the arc will be drawn nearly the full length of the slot. The arc will then be sectionalized by the plates 23 and the coils 21 and 10 22 inserted in series therewith. The coils set up a radial field across the slot 15 as indicated by arrows 33 in Fig. 3 that causes the sectionalized arc to rapidly move therein, and become quickly extinguished in the manner characteristic of this 15 type of device.

It will thus be seen that I have provided an arc-extinguishing device with means for causing the gases generated therein to promote efficient arc extinction. Conducting plates are provided 20 for transferring the arc terminals thereon in order that the terminals may be moved to provide cold cathodes for the arc. When the arc current is below a predetermined value, windings are inserted in series therewith that produce an 25 increased magnetomotive force for moving the arc through the oil that is trapped along the periphery of the slot.

While I have described several embodiments of my invention, it is to be understood by those 30 skilled in the art that many changes, additions, omissions and substitutions may be made therein without departing from the spirit and scope of my invention as set forth in the accompanying claims.

I claim as my invention:

1. The combination with a circuit interrupter having separable contact members for drawing an arc, and a plurality of insulating plates having aligned slots adjacent to the arc path, of magnetic 40 plates associated with a portion of said insulating plates for moving the arc in the space formed by said slots, and a coil associated with the remaining portion of said plates for increasing the force to move the arc when the arc is moved into the 45 slots of the last said portion of the plates.

2. The combination with a circuit interrupter having separable contact members for drawing an arc, and a plurality of insulating plates having aligned slots that are adjacent to the arc path, 50 of magnetic plates associated with a portion of said insulating plates for moving the arc in the space formed by said slots, radial field coils associated with the remaining portion of said plates and means for inserting said coils in series with 55 the arc as the arc is moved in the slots.

3. The combination with a means for establishing an arc, and a plurality of insulating plates having aligned curved slots associated with the arc path, means for moving the arc in the slot 60 when the current thereof is above a predetermined value, and a coil for obtaining arc movement only when the current thereof is below said value.

4. In a circuit interrupter, means for causing 65 an arc, a plurality of conducting members between which the arc plays, some of said conducting members splitting the arc up into a plurality of short sections and one pair of said conducting members having a wide space therebetween leaving a considerable portion of the arc in one section having a length several times the length of each of said short sections, a coil for setting up 70 a magnetic field to rotate the arc among said conducting members, and means which supplies 75

a gas under the action of the arc to extinguish it as it rotates.

5. In an electric switch or circuit breaker, the combination of a fixed and a movable contact piece, a plurality of spaced plates arranged at right angles to the direction of movement of the movable contact, apertures in the plates through which the movable contact can pass, a magnet pole passing through the plates and situated at 10 one side of the said apertures in the plates, and a magnet winding situated at one end of the said magnet pole, the whole being arranged and adapted to break up the arc incident to the opening of a circuit and to simultaneously whirl the arc 15 portions through circular paths between the plates, substantially as described.

6. In an arc extinguisher, means of insulating material having walls for defining a generally annularly shaped narrow slot therebetween, said 20 slot having a relatively long portion permitting a relatively long arc to play therein in one section, a coil having its turns generally concentric with said annularly shaped slot for causing a radial magnetic field across said slot for rotat- 25 ing at least one portion of the arc in the slot, means for initially establishing the arc in said slot and said slot having a material therealong which when acted upon by the arc gives off gas to aid in extinguishing the arc.

30 7. In an arc extinguisher, means of insulating material having walls for defining a generally annularly shaped narrow slot therebetween, said narrow slot having a length at least several times its width in which an arc of considerable length 35 may play in one section, a coil having its turns generally concentric with said annularly shaped slot for causing a radial magnetic field across said narrow slot for moving the arc laterally along said walls, and means along said slot which 40 when acted upon by the arc gives off gas to aid in extinguishing the arc.

45 8. In an arc extinguisher, means of insulating material having walls for defining a generally annularly shaped narrow slot therebetween, said narrow slot having a portion of a length several times its width in which an arc of considerable length 50 may play in one section, a coil having its turns generally concentric with said annularly shaped slot for causing a radial magnetic field across said narrow slot for moving the arc laterally along said walls, and means along said slot which 55 when acted upon by the arc gives off gas, means for venting said narrow slot, and said walls for defining the narrow slot di- recting a blast of fluid toward said venting means and holding the arc in the path of said blast of fluid.

60 9. In a circuit interrupter, means of insulating material having walls defining a substan- 65 tially annularly shaped passage therebetween, a contact member having a portion movable in the passage longitudinally thereof to establish the arc, a coil having its central axis extending longitudinally of the annularly shaped passage adjacent the center thereof for setting up a mag- 70 netic field across the path of said contact mem- ber and across said annularly shaped passage for moving the arc therein, and said annularly shaped passage including means which gives off gas when acted upon by the arc to aid in extinguishing the arc.

75 10. In an arc extinguisher, means of insulating material having a passage therethrough of a generally annular shape, an arc terminal member having an arc path thereon of generally annular

shape, means for initially establishing the arc in said passage in which it may play with one end on said arc terminal member, a coil having its turns generally concentric with said arc terminal member for setting up a magnetic field 5 radially across said passage and causing the arc to rotate in said passage with one end rotating on said arc terminal member, and said passage including a material therealong which gives off gas when acted upon by the arc to aid in extinguishing the arc. 10

11. In an arc extinguisher, means of insulating material having a pair of opposed walls defining a slot having a generally annular shape, an arc terminal member having an arc path thereon 15 of generally annular shape, said slot having a length at least several times its width to permit an arc to play therein in at least one long section with one end of said long section on said arc terminal member, a coil for connection in the 20 circuit to set up a magnetic field across said slot for causing the arc to rotate in the slot with one end rotating on said arc terminal member, and the major part of the slot along its depth 25 being so narrow as to prevent substantially any movement of the arc in a direction lateral to the path of rotation.

12. In an arc extinguisher, means of insulating material having a pair of opposed walls de- 30 fining a slot having a generally annular shape, an arc terminal member having an arc path thereon of generally annular shape, said passage having a length at least several times its width 35 to permit an arc to play therein in at least one long section with one end of said long section on said arc terminal member, a coil having its turns generally concentric with said arc terminal member electrically connected in the circuit to 40 set up a radial magnetic field across said slot for causing the arc to rotate in the slot with one end rotating on said arc terminal member, means along said slot which gives off gas when acted upon by the arc, vents from the slot for said 45 gas, and said slot directing a blast of fluid toward said vents and holding the arc from moving laterally of the direction of rotation of the arc out of the path of said blast of fluid.

13. In an arc extinguisher, means of insulating material having a pair of opposed walls defining a slot having a generally annular shape, a pair 50 of arc terminal members each providing a path for one termini of the arc thereon of generally annular shape, said pair of arc terminal members after the arc is established being spaced apart a distance at least several times the width 55 of the slot to permit a long arc to play therebetween, and said slot of generally annular shape being so narrow over the major part of its depth as to confine the movement of the arc to a pre- 60 determined line, means for causing rotation of the whole length of the arc between said pair of arc terminal members along said line, and means along said slot which gives off gas when 65 acted upon by the arc to aid in extinguishing the arc.

14. In a circuit interrupter, means of insulating material having walls defining a substantially annularly shaped passage therebetween, a contact member having a portion movable in the passage axially thereof to establish the arc, a 70 pair of arc terminal members spaced apart along said means of insulating material a distance at least several times the width of the passage for receiving the arc and permitting it to play in at least one long section, each of said arc terminal 75

members providing a path of generally annular shape on which one terminal of the arc may be moved, means for rotating the whole length of the arc in said passage between said pair of arc terminal members, and said passage having at least part of its length of a substantially uniform narrow width along the major part of the path of rotation, and said passage including means therealong which gives off gas when acted upon by the arc to aid in extinguishing the arc.

15. In a circuit interrupter, means of insulating material having walls defining a substantially annularly shaped passage therebetween, a contact member having a portion movable in the 15 passage axially thereof to establish the arc, a pair of arc terminal members spaced apart along said means of insulating material for receiving the arc, each of said arc terminal members providing a path of generally annular shape on 20 which one terminal of the arc may be moved, a coil for setting up a magnetic field across the path of said contact member and radially across said passage for rotating the arc therein and rotating the terminals of the arc on said pair 25 of arc terminal members, said passage including means therealong which when acted upon by the arc gives off gas, vents from said passage, and said passage being so narrow along the major part of the path of rotation of the arc as to hold 30 the arc against any large amount of movement lateral to the direction of its rotation.

16. In an electro-magnetic device for blowing in a decomposable arc extinguishing fluid the arc of electrical apparatus, substantially uniformly 35 spaced arc horns or electrodes and means for blowing the arc along the electrodes the direction of blowing and that of the electrodes being adapted to displace the complete arc in a direction different from that of the escaping gases resulting from the action of the arc on the extinguishing fluid.

17. In an electro-magnetic device for blowing in a decomposable arc extinguishing fluid the arc of electrical apparatus, substantially uniformly 45 spaced arc horns or electrodes and means for blowing the arc along the electrodes the direction of blowing and that of the electrodes being adapted to displace the complete arc in a direction opposite to that of the escaping gases resulting from the action of the arc on the extinguishing fluid.

18. In oil immersed electric circuit breakers, relatively movable contacts, substantially uniformly spaced electrodes disposed adjacent to the 55 contacts, means to separate these contacts and to cause each of them to be adjacent to the corresponding electrode and electromagnetic blow-out means to blow the arc from the spaced contacts to the electrodes and to displace this arc 60 along these electrodes in a direction different from that of the escaping gases resulting from the action of the arc on the oil.

19. In an electro-magnetic device for blowing in a decomposable arc extinguishing fluid the arc 65 of electrical apparatus, substantially uniformly spaced arc horns or electrodes, means of insulating material forming a substantially annularly shaped passage between said electrodes and means for blowing the arc in said passage 70 along the electrodes, the direction of blowing and that of the electrodes being adapted to displace the complete arc in a direction different from that of the escaping gases resulting from the action of the arc on the extinguishing fluid.

75. 20. In an electro-magnetic device for blowing

the arc of electrical apparatus, substantially uniformly spaced arc horns or electrodes, means of insulating material forming a substantially annularly shaped passage between said electrodes, said passage having material therealong which forms gas when acted upon by an arc, and means for blowing the arc along the electrodes, the direction of blowing and that of the electrodes being adapted to displace the complete arc in a direction different from that of the escaping 10 gases resulting from the action of the arc on said material.

21. In an electric circuit breaker, relatively movable contacts, substantially uniformly spaced electrodes disposed adjacent to the contacts, 15 means to separate these contacts and to cause each of them to be adjacent to the corresponding electrode, a material along the arc which gives off gas when acted upon by the arc, and electromagnetic blow-out means to blow the arc from 20 the spaced contacts to the electrodes and to displace this arc along these electrodes in a direction different from that of the escaping gases resulting from the action of the arc on said material.

22. In an arc extinguisher, means of insulating 25 material having walls for defining a generally annularly shaped narrow slot therebetween, said narrow slot having a portion of considerable length in which an arc of considerable 30 length may play in one section, a coil for magnetically moving the arc laterally along said walls, a plurality of recesses along one or more of said walls of the slot, and said slot having means therealong which when acted upon by the arc gives off gas to aid in extinguishing the arc.

23. In an arc extinguisher, means of insulating material having a pair of opposed walls defining a slot having a generally annular shape, an arc terminal member having an arc path thereon of generally annular shape, said slot being positioned and having sufficient length to permit an are to play therein in at least one long section with one end of said long section on said arc terminal member, a coil for causing the arc to rotate in the slot with one end rotating on said arc terminal member, and substantially the whole of said slot being so narrow as to prevent substantially any movement of the arc in a direction lateral to the path of rotation and a plurality of recesses distributed over one wall of said slot.

24. In an electric switch or circuit breaker, the combination of a fixed and a movable contact piece, a plurality of spaced plates arranged at right angles to the direction of movement of the movable contact, apertures in the plates 55 through which the movable contact can pass, means for providing a magnetic field having its central longitudinal axis passing through the plates and situated at one side of the said apertures, said means including a winding situated 60 at one end of the structure, the whole being arranged and adapted to break up the arc incident to the opening of a circuit and to simultaneously whirl the arc portions along circular paths between the plates substantially as described.

25. In an electric switch or circuit breaker, the combination of a fixed and a movable contact piece, a plurality of spaced plates arranged at right angles to the direction of movement of the movable contact, apertures in the plates through 70 which the arc drawn by the movable contact can play, a magnet pole passing through the plates and situated at one side of the said apertures in the plates, and a magnet winding situated at one end of the said magnet pole, the whole being 75

arranged and adapted to break up the arc incident to the opening of a circuit and to simultaneously whirl the arc portions through circular paths between the plates, substantially as described.

26. In an arc extinguisher, a plurality of spaced plates of conducting material each providing an annularly shaped path for the arc, a coil which when energized sets up a radial magnetic field across said annularly shaped arc paths, an opening through a plurality of said plates of conducting material, said opening having a portion within in said radial magnetic field, means for causing an arc to play in said opening, and said radial magnetic field set up by the coil causing the arc to move along said annularly shaped paths.

27. In an arc extinguisher, a plurality of members of conducting material between which the arc may be split up into shorter arcs, said conducting members each providing a path along which the short arcs may be rotated, a coil which when energized sets up a magnetic field for rotating the arcs, an opening through a plurality of said members of conducting material, means for causing an arc to play in said opening, and said opening having a portion within the magnetic field for rotating the arc.

28. In an electric switch or circuit breaker, the combination of a fixed and a movable contact piece, a structure including means of insulating material having an aperture through which the movable contact can pass, a magnet pole passing through the structure and situated at one side of the said aperture through the structure, and a magnet winding situated at one end of the said magnetic pole, the whole being arranged and adapted to whirl the arc through a circular path in the structure.

29. In a circuit interrupter, the combination of means for establishing an arc, a structure of insulating material having an aperture for said means for establishing the arc, said aperture having a generally circular portion in which the arc may be rotated, a magnet winding having its central axis passing through the structure at one side of the said aperture and adjacent the center of said circular portion of the aperture, said magnet winding when energized setting up a radial magnetic field across said means for establishing the arc and across said circular portion of the aperture for rotating the arc therein.

30. In a circuit interrupter, the combination of means for establishing an arc, an arc extinguishing structure having an aperture in which the arc is established by said means, said aperture having walls of insulating material and having an annularly shaped portion in which the arc may be rotated, a magnet winding having its central axis passing through the structure and situated at one side of and generally parallel to the path through said aperture along which the arc is established, said magnet winding when energized setting up a radial magnetic field across said portion of the aperture where the arc is established and across said annularly shaped portion of the aperture for moving the arc therein.

31. In a circuit interrupter, the combination of means for establishing an arc, an arc extinguishing structure having an aperture in which the arc is established by said means, said aperture having walls of insulating material and having an annularly shaped portion in which the arc may be rotated, said annularly shaped portion of the aperture closely confining the arc and having a material therealong which when acted

upon by the arc gives off gas to aid its extinction, a magnet winding having its central axis passing through the structure and situated at one side of and generally parallel to the path through said aperture along which the arc is established, said magnet winding when energized setting up a radial magnetic field across said portion of the aperture where the arc is established and across said annularly shaped portion of the aperture for moving the arc therein along said gas forming material.

32. In a circuit interrupter, the combination of means for establishing an arc, an arc extinguishing structure having an aperture in which the arc is established by said means, said aperture having walls of insulating material and having an annularly shaped portion in which the arc may be rotated, a pole piece of magnetic material passing through the structure adjacent the center of said annularly shaped portion of the aperture generally parallel to the path along which the arc is established, a magnet winding around said pole piece, said winding when energized causing a radial magnetic field across said portion of the aperture where the arc is established and across said annularly shaped portion of the aperture for moving the arc therein.

33. In a circuit interrupter, the combination of means for establishing an arc, an arc extinguishing structure having an aperture in which the arc is established by said means, said aperture having walls of insulating material and having an annularly shaped portion in which the arc may be rotated, said annularly shaped portion of the aperture closely confining the arc and having a material therealong which when acted upon by the arc gives off gas to aid its extinction, a pole piece of magnetic material passing through the structure adjacent the center of said annularly shaped portion of the aperture generally parallel to the path along which the arc is established, a magnet winding around said pole piece, said winding when energized causing a radial magnetic field across said portion of the aperture where the arc is established and across said annularly shaped portion of the aperture for moving the arc therein.

34. In a circuit interrupter, the combination of means for establishing an arc, an arc extinguishing structure having an aperture in which the arc is established by said means, said aperture having walls of insulating material and having an annularly shaped portion in which the arc may be rotated, an arc terminal member at at least one end of the aperture and having an annularly shaped portion on which one end of the arc is rotatable, a magnet winding having its central axis passing through the structure and situated at one side of and generally parallel to the path through said aperture along which the arc is established, said magnet winding when energized setting up a radial magnetic field across said portion of the aperture where the arc is established and across said annularly shaped portion of the aperture for moving the arc therein.

35. In a circuit interrupter, the combination of means for establishing an arc, an arc extinguishing structure having an aperture in which the arc is established by said means, said aperture having walls of insulating material and having an annularly shaped portion in which the arc may be rotated, said annularly shaped portion of the aperture having a length at least several times its width to permit the arc to play therein in at least one long section, a magnet winding having

its central axis passing through the structure and situated at one side of and generally parallel to the path through said aperture along which the arc is established, said magnet winding when energized setting up a radial magnetic field across said portion of the aperture where the arc is established and across said annularly shaped portion of the aperture for moving the arc therein.

36. In a circuit interrupter, the combination of means for establishing an arc, an arc extinguishing structure having an aperture in which the arc is established by said means, said aperture having walls of insulating material and having an annularly shaped portion in which the arc may be rotated, said annularly shaped portion of the aperture having a length at least several times its width to permit the arc to play therein in at least one long section, an arc terminal member at at least one end of the aperture and having an annularly shaped portion on which one end of the arc is rotatable, a magnet winding having its central axis passing through the structure and situated at one side of and generally parallel to the path through said aperture along which the arc is established, said magnet winding when energized setting up a radial magnetic field across said portion of the aperture where the arc is established and across said annularly shaped portion of the aperture for moving the arc therein.

37. In a circuit interrupter, the combination of means for establishing an arc, an arc extinguishing structure having an aperture in which the arc is established by said means, said aperture having walls of insulating material and having an annularly shaped portion in which the arc may be rotated, said annularly shaped portion of the aperture closely confining the arc and having a material therealong which when acted upon by the arc gives off gas to aid its extinction, a vent from the aperture which is open during the extinguishing of the arc to permit the escape of the gas, a magnet winding having its central axis passing through the structure and situated at one side of and generally parallel to the path through said aperture along which the arc is established, said magnet winding when energized setting up a radial magnetic field across said portion of the aperture where the arc is established and across said annularly shaped portion of the aperture for moving the arc therein in along said gas forming material.

38. In a circuit interrupter, the combination of means for establishing an arc, an arc extinguishing structure having an aperture in which the arc is established by said means, said aperture having walls of insulating material and having an annularly shaped portion in which the arc may be rotated, said annularly shaped portion of the aperture having a length at least several times its width to permit the arc to play therein in at least one long section, an arc terminal member at at least one end of the aperture and having an annularly shaped portion on which one end of the arc is rotatable, said annularly shaped portion of the aperture closely confining the arc and having a material therealong which when acted upon by the arc gives off gas to aid its extinction, a vent from the aperture which is open during the extinguishing of the arc to permit the escape of the gas, a magnet winding having its central axis passing through the structure and situated at one side of and generally parallel to the path through said aperture along which the arc is established,

said magnet winding when energized setting up a radial magnetic field across said portion of the aperture where the arc is established and across said annularly shaped portion of the aperture for moving the arc therein along said gas forming material.

39. In an arc extinguisher for circuit breakers, means of insulating material defining the walls of a slot-like substantially enclosed arc passage, means for drawing an arc longitudinally of the passage, and means for moving the arc laterally along said passage, the said walls of said passage being gradually convergent in the direction of arc movement from the entrance of said passage for gradually restricting the cross-section of the arc, said side walls also having opposed inwardly projecting longitudinally spaced ribs for restricting portions of the arc without materially increasing the resistance to movement of the arc along said passage.

40. In an arc extinguisher for circuit breakers, means of insulating material defining the walls of a slot-like substantially enclosed arc passage, means for drawing an arc longitudinally of the passage, and means for moving the arc laterally along said passage, the said walls of said passage being gradually convergent in the direction of arc movement from the entrance of said passage for gradually restricting the cross-section of the arc, said side walls also having opposed inwardly projecting longitudinally spaced ribs for restricting portions of the arc without materially increasing the resistance to movement of the arc along said passage, and a material within said passage which gives off a gas when acted upon by an arc to aid in extinguishing the arc, the side walls of said passage having pockets positioned therein between said ribs for retaining said gas producing material along said passage.

41. In an arc extinguisher for circuit breakers, means of insulating material defining the walls of a slot-like substantially enclosed arc passage, means for drawing an arc longitudinally of the passage, and means for moving the arc laterally along said passage, said passage gradually decreasing in width from the entrance thereof in the direction of arc movement for restricting the cross-section of said arc, longitudinally spaced portions of the side walls of said passage decreasing in width in the direction of arc movement at a greater rate than the remaining portions of said side walls to contract the arc stream into a plurality of restricted sections and to increase the creepage distance lengthwise of said passage.

42. In an arc extinguisher for circuit breakers, means of insulating material defining the walls of a slot-like substantially enclosed arc passage, said passage being enlarged at the entrance thereof, a pair of separable contacts within said enlarged portion for establishing an arc longitudinally of said passage, means for moving said arc laterally along said passage, said passage having a tapering portion extending from said enlarged portion in the direction of arc movement for gradually restricting the cross-section of the arc, the walls of said passage having ribs spaced longitudinally of the passage and extending from the enlarged entrance portion toward the rear of the passage for contracting said arc into a plurality of restricted sections without materially increasing the resistance to movement of the arc along said passage, and a liquid within said passage which gives off a gas.

when acted upon by said arc to aid in extinguishing the arc.

43. In an arc extinguisher, means of insulating material having walls for defining a generally annularly shaped narrow slot therebetween, said narrow slot having a length at least several times its width in which an arc of considerable length may play in one section, a coil having its turns generally concentric with said 10 annularly shaped slot for causing a radial magnetic field across said narrow slot for moving the arc laterally along said walls, means along said slot which when acted upon by the arc gives off gas to aid in extinguishing the arc, and venting means for conducting the gas produced by the arc exteriorly of said narrow slot, said venting means being disposed with respect to said 15

narrow slot and the arc path therein to cause a flow of gas through the arc stream.

44. In an arc extinguisher, means of insulating material having walls for defining a generally annularly shaped narrow slot therebetween, said narrow slot having a portion of considerable length in which an arc of considerable length may play in one section, a coil for magnetically moving the arc laterally along said walls, a plurality of recesses along one or more of said walls 10 of the slot, said slot having means therealong which when acted upon by the arc gives off gas to aid in extinguishing the arc, and vents along said slot for the escape of gas therefrom, the walls of said slot directing a flow of gas through 15 the arc toward said vents.
